D. E. RICE

WEEDER

Filed Nov. 13, 1922

Inventor

D. E. Rice

By *Watson B. Coleman*
Attorney

UNITED STATES PATENT OFFICE.

DANIEL E. RICE, OF DUKE, OKLAHOMA.

WEEDER.

Application filed November 13, 1922. Serial No. 300,599.

To all whom it may concern:

Be it known that I, DANIEL E. RICE, a citizen of the United States, residing at Duke, in the county of Jackson and State 5 of Oklahoma, have invented certain new and useful Improvements in Weeders, of which the following is a specification, reference being had to the accompanying drawings.

This invention relates to certain improvements in weeders, and it is an object of the invention to provide a novel and improved device of this general character which is adapted to be used in connection with a lister cultivator or the like and which operates in a manner to destroy weeds between the rows and on the beds.

Another object of the invention is to provide a novel and improved device of this general character which is particularly adapted for use in connection with the cultivation of cotton, corn, maize and the like, and wherein cutting elements are carried by runners suitably hitched or connected with the cultivator proper.

The invention consists in the details of construction and in the combination and arrangement of the several parts of my improved weeder whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is an elevational view of a weeder 40 constructed in accordance with an embodiment of my invention, the coacting cultivator being diagrammatically indicated by dotted lines; and

Figure 2 is a view in perspective of my improved weeder as herein set forth.

My improved weeder as herein disclosed comprises a pair of spaced parallel runners 1, each being provided at its forward end portion with an upstanding and forwardly inclined plate or hanger 2, preferably of steel, and which has its upper or free end portion terminating in an outwardly disposed flange 3, said flange 3 being substantially perpendicularly related to the hanger 50 2. The flange 3 is adapted to be coupled,

as indicated at 4 in Figure 1, to a convenient part of the cultivator proper such as a downwardly and rearwardly inclined arm 5 positioned substantially immediately to the rear of a guide wheel 6.

The rear portions of the runners 1, adjacent their upper margins, are provided with the inwardly directed arms 7 in overlying relation, said overlying portions being provided with the slots 8 through which is directed a clamping element 9. The element 9, preferably comprises a headed shank or bolt and a coacting nut. The forward portions of the runners 1 are also provided with the inwardly directed overlying arms 10 provided with the registering slots 11 through which is directed a clamping medium 12. The arms 8 and 9 and the associated clamping means 9 and 12 coacting therewith provide means whereby the runners 1 may be effectively maintained in different positions one with respect to the other, as the requirements of practice may necessitate.

Carried by each of the runners 1 is an elongated knife 14, said knife when in applied position extending rearwardly and outwardly of the runner on a predetermined incline. The forward portion of the runner is provided with an upstanding flange 15 substantially at right angles to the blade 14, 85 but extending obliquely theracross. This flange 15 is provided with an extension 16 which is pivotally connected as at 17 with the associated runner 1. The extension 16, outwardly of the pivotal connection 17, is 90 provided with a transversely disposed arcuate slot 18 disposed on a curvature concentric to the pivot 17.

Carried by the runner 1 and disposed through the slot 18 is a shank 19 with which 95 is engaged a clamping nut or member 20. The blade 14 may be adjusted as preferred about the pivotal connection 17 and held in such adjustment upon tightening of the nut and member 20. My improved weeder when 100 applied is adapted to travel between the rows, and the blades 14 are of such length as to effectively destroy the weeds upon the row and bed. My improved weeder is particularly adapted for use in connection with the cultivation of cotton, corn or maize and the like, and is further particularly adapted for use in connection with a double row cultivator. While I only show one of my improvements in the accompanying draw- 110

ings, it is to be understood that a device constructed in accordance with an embodiment of my invention will be suitably positioned at opposite sides of the cultivator.

From the foregoing description it is thought to be obvious that a weeder constructed in accordance with my invention is particularly well adapted for use by reason of the convenience and facility with which 10 it may be assembled and operated, and it will also be obvious that my invention is susceptible of some change and modification without departing from the principles and spirit thereof and for this reason I do not 15 wish to be understood as limiting myself to the precise arrangement and formation of the several parts herein shown in carrying out my invention in practice except as hereinafter claimed.

What is claimed is:—

A weeding device comprising a pair of spaced runners substantially in parallelism, an upwardly disposed and forwardly inclined plate secured to the forward end portion of each of the runners, the upper end portion of the plate terminating in an outwardly disposed flange substantially perpendicularly related to the hanger, said flange providing means for attaching the hanger to a rearwardly directed arm carried by a cultivator, means for connecting the runners and maintaining the same in desired spaced relation, and cutting blades extending outwardly and rearwardly from the runners. 25 30 35

In testimony whereof I hereunto affix my signature.

DANIEL E. RICE.
